(57) **CLAIM**

The ornamental design for a vehicle mount, as shown and described.

DESCRIPTION

FIG. 1 is a front-top-right perspective view of a vehicle mount showing our new design;

FIG. 2 is a left-side view thereof;

FIG. 3 is a right-side view thereof;

FIG. 4 is a front view thereof;

FIG. 5 is a back view thereof;

FIG. 6 is a top view thereof; and,

FIG. 7 is a bottom view thereof.

The broken lines shown in the drawings depict portions of the vehicle mount that form no part of the claimed design.

1 Claim, 7 Drawing Sheets

See application file for complete search history.
